(57) **CLAIM**

The ornamental design for a tablet holder stand, as shown and described.

DESCRIPTION

FIG. 1 is a front view of a tablet holder stand (e.g., a holder stand for a tablet device, such as a tablet computer or other tablet-shaped electronic device), showing our new design; FIG. 2 is a rear view thereof; FIG. 3 is a right side view thereof; FIG. 4 is a left side view thereof; FIG. 5 is a top view thereof; FIG. 6 is a bottom view thereof; FIG. 7 is a top-front-left perspective view thereof; FIG. 8 is a top-rear-left perspective view thereof; FIG. 9 is a top-rear-right perspective view thereof; FIG. 10 is a top-front-right perspective view thereof; FIG. 11 is a bottom-front-left perspective view thereof; FIG. 12 is a bottom-rear-left perspective view thereof; FIG. 13 is a bottom-rear-right perspective view thereof; and, FIG. 14 is a bottom-front-right perspective view thereof. The shade lines show surface contour.
